(57) CLAIM

What is claimed is the ornamental design for a brick appearance molded landscape panel, as shown and described.

DESCRIPTION

FIG. 1 is a perspective view of the brick appearance molded landscape panel;

FIG. 2 is a front view thereof;

FIG. 3 is a back view thereof;

FIG. 4 is a top view thereof;

FIG. 5 is a bottom view thereof;

FIG. 6 is left end view thereof; and,

FIG. 7 is a right end view thereof.

The broken lines depict portions of the brick appearance molded landscape panel that forms no part of the claimed design.
